DAVID J. BARKER, OF SEATTLE, WASHINGTON

CASEMENT WINDOW SWINGING MEANS

Application filed April 22, 1929. Serial No. 357,038.

Casement windows have certain advantages, such as the ability to open the entire area of the window frame, but frequently their disadvantages outweigh their advantages. Thus, a casement window, swinging outwardly, cannot be conveniently screened, or the screen obstructs the access to the window necessary to adjust it to position; if a roll screen is used it is expensive, in the first place, and not altogether tight. If the casement window should swing inside it interferes with curtains, shades, hangings, or drapes, and such windows are seldom swung in this manner.

It is an object of this invention, therefore, to provide a casement window and a means for screening the same, by means of which the casement window may be swung from a full open to a closed position, and by means of which it can be adjusted with the screen in place, without removing the screen, and retained in any selected position. It is also a further object to accomplish the above results without any disturbance of the shades, curtains, hangings or drapes, and to so mount the screen that it may be readily removed when its presence is not desired.

A further object is the provision of inexpensive, yet thoroughly reliable, tight, and convenient screening means for casement windows.

A further object is the provision of operating means for such a combination, particularly for the casement window, by means of which the latter may be moved from within the room, and with a screen in place between the operator and the casement window which is being moved.

A further object is the provision of a mechanism for controlling and operating the casement window, which is readily adaptable, without change of construction, to windows which swing from either side of the window frame.

Other objects, and particularly such as relate more purely to structural details, may be ascertained from a study of the drawings which are attached hereto, of the following specification, and of the claims which terminate the same.

My invention comprises the novel parts, and the novel combination and arrangement thereof, together with subcombinations, as are shown in the accompanying drawings, described in the specification, and as will be more particularly defined by the claims which terminate the same.

In the accompanying drawings I have shown my invention arranged in a typical installation, it being understood that changes in the arrangement of the parts, and in the details of construction, may be made, within the scope of the appended claims, and without departure from the principles of my invention.

Figure 1 is an outside elevation of a casement window, showing my screen in position in the window frame, and the casement window partly open.

Figure 2 is a section of the same on a horizontal plane.

Figure 3 is a section through the sill, and parts associated therewith, the screen being shown as thrown out of the way, and the casement window being closed.

Figure 4 is a detail, in plan, with parts shown in section on a horizontal plane, and arranged in the positions of Figure 3, a cover plate being omitted for clearness of illustration.

Figure 5 is a view similar to Figure 4 of the swinging end of the window, and its relation to the screen and frame when the screen is in position.

Figure 6 is a detail in plan view, and Figure 7 is a detail section on the line 7-7 of Figure 2.

In the construction, arrangement, and mounting of the casement window 1, and its frame 2, my invention does not differ from that of the ordinary or usual casement window. The casement window is shown as pivoted in the usual way by the hinges 10 to the frame 2 at one side or the other of the frame. The frame includes the usual sill, composed of the inner member 20, and the outer sloping member 21, the two joined in such a way as to leave an outwardly facing shoulder 22, against which the window seats when closed. The top and side members of the frame may

have shoulders in the same plane as the shoulder 22, as this is ordinarily the case, but this is not essential so far as the present invention is concerned.

6 A screen 3 is made of a size to fit within the frame 2, preferably in a plane parallel to and just inwardly of the plane occupied by the window 1 when closed. This permits the window to swing freely without interfering with the screen, and the latter is far enough out to avoid interference with shades and the like, hung from the frame 2. As the window 1 seats against the shoulder 22, the screen would ordinarily be just enough smaller to seat upon the inside sill member 20. This screen may assume various shapes, and be mounted in a number of different ways, so far as concerns the member for operating the window 1, but for convenience I prefer 10 that it be hinged, as is indicated at 30, at the opposite side of the frame 2 from the hinges 10 of the window 1. I prefer, further, that it be made articulated, and it is shown as composed of two sections, the outer one hinged 15 upon the inner one, as is indicated at 31 in Figure 2. The hinges 30 are of somewhat special design, whereby their pivot axis is outwardly of the plane of the screen when closed, thereby throwing the screen, when 20 folded and swung outwardly, into the dotted line position of Figures 1 and 2 (see particularly the latter). There it may be engaged by any suitable holding means, such as the stop 4 and catch 40, the latter being pivoted 25 and carrying a weight 41, whereby it will be pushed aside as the screen swings open and engages it, and will rise again to catch and hold the screen in position against the stop 4, where it will not rattle in the wind. 30 Casement windows frequently carry a lever catch 11, engageable with a complementary member in the frame, and serving as a handle to move the window. This can be operated only through the frame, if the window swings 35 outwardly, as is customary, and hence it will not be possible to operate the window by this lever 11, or to engage the same with its complementary member, except as the screen 3 is removed from its operative position, nor is 40 it possible to adjust the window with the screen in place, except by a type of mechanism corresponding to that which I will now describe.

50 This window swinging mechanism includes a member engageable by the operator, as, for example, the turn button or handle 50, and a member engageable with the window, as the link 51. Intermediate these members is a member which can translate the turning 55 movement of the operating handle or button 50 into longitudinal movement of the link 51. This may take the form of a transversely movable bar 5, to one end of which the link 51 is removably pivoted, as indicated at 52, and the transverse movement of the bar 5

may be accomplished by forming it as a rack bar with teeth facing inwardly, with which are meshed the teeth of a pinion 53. The operating handle 50 may be secured to the pinion 53, or the shaft of the latter, or a second pinion 54 may be employed, in mesh with the pinion 53, and this pinion 54 may be made somewhat smaller than the pinion 53, to give added force to the window swinging means.

70 75

The link 51 being pivoted at 55 to the casement window 1, and the rack bar 5 being suitably guided, by means to be hereafter described, transverse movement of the rack bar from the position shown in Figure 4 will cause the window to be projected outwardly, as the rack bar 5 moves laterally. This movement can be stopped at any selected location by projecting a locking dog 6 between the teeth of some member of the pinion and rack system, as, for example, between the teeth of the pinion 53. It might as well be projected between the teeth of the rack bar 5, or of the pinion 54. Preferably, this dog 6 is pivoted at 60 upon a suitable support, in the form of a plate 7, and is actuated by a link 61, slidable in a curved slot 62 in the plate 7, so that movement of the locking handle 63 secured to the link 61 will project the dog into position between two adjacent 80 teeth of the pinion, and will move the locking handle or pin 63 into position where the side of the slot 62 is in effect a shoulder, normal to the line from pin 63 to the tip of dog 6, which prevents reverse movement of the dog 90 when acted upon by a force applied to the window, as, for example, the wind tending to swing the window open or shut. Only by movement of the pin 63 in the slot 62 can the dog 6 be withdrawn.

95 100 105

The rack bar 5 and the pinion means in mesh therewith, together with the locking dog 6 and its operating means, may all be conveniently mounted upon the cover plate 7. Preferably, the sill member 20 is recessed, 110 as may be seen at 25 in Figure 4, to receive the various operating members, and the cover plate 7, in which the pinions are journaled, may be set flush with the upper surface of this sill member 20, though still above the surface of the inclined sill member 21. The cover plate 7 may be bent, and cooperates with flange plates 74 and 77, to form a guide 75 (see Figure 7) for the rack bar 5, 115 whereby the rack bar 5 is carried at the outer edge of the cover plate 7, and a slot 76 is left therebelow for the connection of the link 51 to the rack bar. The flange plate 74 forms an apron extending downwardly nearly to the outer sill member 21, but inward from the edge enough to leave a recess for the reception of link 51 when the window is closed. To close the recess 25 in the uppersill member, to keep out rain, an upwardly flanged plate 73 may be secured upon the sill member 21,

120 125 130

this contacting with and cooperating with the apron 74 to form a water tight joint, thus protecting the operating parts of the mechanism.

5 With the screen 3 in place, the window 1 may be moved from any position, substantially closed, to the limit of its outward swing, merely by turning the handle 50. It is not necessary to remove the screen for this 10 operation, since the link 51, the only member which extends outwardly of the plane of the window 1, extends underneath the lower edge of the screen 3, when the latter is in place. It lies beneath the edge of this screen, and in 15 the outwardly facing surface of the shoulder 22. As will be understood, the link 51 is engaged beneath the lower face of the rack bar 5, through the slot 76.

Now, if it is desired to remove the screen, 20 it is necessary, only, to swing the window 1 open, and in this form of the screen to break the screen at the hinge 31, holding the two parts together, and swinging them outwardly into the dotted line position of Figure 2. The 25 window 1 may not be ordinarily closed completely with the screen 3 in place, since the handle 31 would strike the screen 3 and prevent this, but, nevertheless, this handle may be omitted, or a recess may be formed in the 30 screen 3, thus permitting complete closing of the window with the screen in place. However, this is not important, as whenever the window is closed the screen has no function, and might as well be out of the way.

35 It will be noted that the window swinging mechanism may be employed with windows which swing either from the right or from the left side. It may be let into either side of the sill, and if it is desired to swing a window 40 which is hinged at the opposite side to the window shown in Figure 2 or 4, it is necessary only to disconnect the link 51 at its connection at 52 to the rack bar 5, and connect to the other end of the rack bar, as is indicated at 45 56, or to remove the rack bar 5 from its guide 75, turn it upside down, and to connect the link again at the under side of the rack bar. It now slides from the left, as seen in Figure 50 4, rather than from the right, to open the window. Thus, it is necessary to manufacture only a single device, which will accomplish all of the purposes to which it may be put.

55 It will be noted that various types of screens might be employed. It is not essential that the screen be articulated, or even that it be a swinging type of screen, for the operating mechanism will swing the window, 60 whatever type of screen be interposed between the operator and the window. As a matter of fact, it is not essential that the screen be employed, as my device will serve as a means for swinging casement windows, 65 irrespective of the screen, and furnishes a

convenient means of holding the window in any selected position.

What I claim as my invention is:

1. A window swinging means for screened casement windows adapted for securement in the window sill, the sill being recessed in its upper and outer faces to receive the window-swinging means, an upwardly flanged plate closing the outside of said recess, a transverse 70 guide above and outwardly of said flange, an apron depending therefrom and contacting with said flange to seal the outer side of the recess, a cover plate closing the upper side thereof, a member transversely slidable in said guide, means operable from a point inwardly of the screen for sliding said member, and a link connecting said member and the window.

2. A window swinging means for screened casement windows adapted for securement in the window sill, the sill being recessed in its upper and outer faces to receive the window-swinging means, a cover plate closing the upper side of the recess and having a transverse 85 guide in its outer edge, and a downward flange, an upwardly flanged plate cooperating with said downward flange to close the outer side of the recess, a rack bar with its teeth inward slidably in said guide, a link 90 releasably pivoted to the window and the under side of the rack bar, and pinion means supported on said cover plate, in mesh with 95 said rack bar, for moving the same.

3. A casement window operating means comprising a support adapted for securement to the window frame and having a guide extending transversely when thus secured, a member slidable in said guide, means supported from said support, inwardly of said member, for sliding the same, and an operating link connection extending outward from said member for connection to a window, and operable upon movement of the member in one direction to swing the window shut, and upon movement of the member in the opposite direction to open the window.

4. A casement window operating means as in claim 3, the sliding member comprising a rack, and the means for sliding the same including a pinion in mesh therewith, and the operating link connection from the rack being adapted for connection by a removable pivotal connection to the under side of said rack at either end.

5. A casement window operating means as in claim 3, the sliding member comprising a rack, and the means for sliding the same including a pinion in mesh therewith and means for rotating the same, and a dog movable at will into and from engagement between the teeth of said pinion to retain parts in a selected position.

6. A casement window operating means as in claim 3, including a toothed member, and a dog movable into and from engagement 130

between the teeth of said toothed member, and a member engageable for operation of the dog, said support being slotted for projection of said member, said slot being curved to form a shoulder, when in locked position, against which the dog-operating member bears to prevent accidental disengagement of the dog.

7. A window swinging means for screened casement windows comprising a transverse guide adapted for securement in the window sill, and a rack bar slidable therein, a link pivoted to the said rack bar at a point spaced inward, in window-closed position, from the window hinge axis, and adapted to be secured to the window, and pinion means meshed with said rack bar and rotatable from within the plane of the screen.

Signed at Seattle, Washington, this 10th day of April, 1929.

DAVID J. BARKER.
